Associated Electric Laboratories, Inc., Chicago,
Ill., a corporation of Delaware

Application April 16, 1938, Serial No. 202,392

12 Claims. (Cl. 179—81)

The present invention relates to telephone systems and more particularly to substation apparatus for use in a telephone system.

Various circuit arrangements have been used in the past for preventing the audio frequency energy developed by the operation of a substation transmitter from being delivered to the receiver or sound reproducing device of the substation for reproduction. A circuit provided for this purpose is conventionally known as an anti-side-tone circuit and is in effect an alternating current bridge having the sound reproducing device coupled to two arms of the bridge in a manner such that substantially zero voltage is developed across the input terminals of the sound reproducing device during operation of the transmitter. When a substation circuit of this character is involved in a communication connection to another substation of the system, one arm of the anti-side-tone bridge circuit is partially made up of the equivalent impedance, measured at the substation line terminals, of the series and shunt resistance and the shunt capacitance of the two lines, the impedance of the coupling elements included in the line connecting apparatus of the line terminating exchange and the impedances of the respective circuit elements provided or embodied in the distant substation. For satisfactory operation of the anti-side-tone substation circuit, it is necessary to provide therein a balancing network having a frequency impedance characteristic which is substantially the same as that of the measured equivalent impedance throughout the operating audio frequency range. When regular subscribers' lines of substantial length are involved in the communication connection, the predominant component impedances of the measured equivalent impedance are the series resistance and the shunt capacitance of the two connecting lines. More particularly, in the case of a connection including two long subscribers' lines, the components of the equivalent impedance measured at the line terminals of one substation and represented by the circuit elements at the distant substation and by the coupling elements embodied in the line connecting equipment of the line terminating exchange, are relatively small as compared to the series resistance and shunt capacitance of the two connecting lines and, hence, may be neglected in designing a satisfactory balancing network. In this case, a simple resistance-capacitance balancing network will provide a reasonably good balance of the anti-side-tone bridge over the major portion of the audio frequency

range. In an arrangement of the type commonly found in private exchanges wherein the substation lines are short, however, the series resistance and shunt capacitance of the two substation lines involved in a communication connection are relatively small and the effect of the coupling elements included in the line connecting equipment of the line terminating exchange and of the circuit elements provided at the distant substation are predominant, so that a simple 10 resistance-capacitance network is, over the greater portion of the audio frequency range, of little effect in balancing an anti-side-tone substation circuit.

It is an object of the present invention to provide in an arrangement of the character described an improved anti-side-tone substation circuit so arranged that the circuit is substantially balanced at all frequencies within the operating range when included in a communication connection to a distant substation wherein the impedances of the coupling elements embodied in the line connecting equipment of the line terminating exchange and of the circuit elements provided at the distant substation are predominant 25 in determining the equivalent impedance forming a part of one arm of the anti-side-tone bridge circuit.

It is another object of the invention to provide an improved and effective balancing network of 30 simple arrangement for use in a substation circuit of the anti-side-tone type.

The invention is illustrated as being incorporated in a telephone system wherein a first substation circuit of the anti-side-tone type is provided with a pair of line terminals which are adapted to be connected by way of a telephone line, the line connecting equipment of an exchange and a second line to another substation. The exchange is of the private automatic type such that the two substation lines involved in a communication connection including the first substation circuit are relatively short and the equivalent impedance, measured at the line terminals of the first substation, of impedance elements external to or not directly included in the first substation circuit is substantially determined by the component impedances of the coupling elements embodied in the line connecting equipment of the exchange and the component impedances of the 40 circuit elements included in the circuit of the distant substation. In accordance with the present invention, there is provided in the anti-side-tone substation circuit a network for balancing the 45 equivalent impedance, measured across the line 50 55

terminals of the circuit, which comprises a plurality of impedance elements having impedances individually corresponding to certain of the component impedances making up the measured equivalent impedance. The impedance values of the plurality of impedance elements are so proportioned relative to their corresponding component impedances and the elements of the network are so connected and arranged that the anti-side-tone circuit is substantially balanced at all frequencies within the operating frequency range. More particularly, there is provided in the balancing network, impedance elements which individually correspond to the coupling elements embodied in the line connecting equipment of the line terminating exchange and to the transmitter, receiver and inductance coil embodied in the distant substation circuit. Additional impedance elements are included in the balancing network which individually correspond to the lumped series and shunt resistances of the two connecting lines and to the lumped shunt capacitance of these lines. All of these elements are so proportioned and so connected and arranged that excellent anti-side-tone effect is realized at all frequencies within the audio range.

Further features of the invention pertain to the particular arrangement of the circuit elements whereby the above objects are attained.

30 The novel features believed to be characteristic of the invention are set forth with particularity in the appended claims. The invention, both as to its organization and method of operation, together with further objects and advantages thereof, will best be understood by reference to the specification taken in connection with the accompanying drawings in which Figure 1 illustrates an automatic telephone system having incorporated therein a substation circuit connect-
40 ed and arranged in accordance with the present invention; Fig. 2 illustrates the circuit of an established communication connection between the two substations shown in Fig. 1; Fig. 2a illustrates the equivalent circuit formed by combining certain of the impedances shown in Fig. 2; and Fig. 3 illustrates the structural arrangement of one of the circuit elements shown in Figs. 1 and 2.

Referring now more particularly to Fig. 1 of the drawings, the system there illustrated comprises 50 a plurality of telephone lines, two of which are indicated at 10 and 11 terminating in the line connecting or line switching equipment of a private automatic exchange 12. The line switching equipment provided in the exchange 12 for setting up connections between the various lines of the systems may be of any desired impulse responsive type and, since the particular character and arrangement of this equipment forms no part in the present invention, the exchange has 55 been only diagrammatically illustrated. It will be understood, however, that this switching equipment includes the usual non-numerical switches such for example, as line switches, and the usual numerical switches of the impulse responsive type 60 which are conventionally known as selector and connector switches.

The end of each of the telephone lines remote from the switching equipment provided in the exchange 12 terminates in a substation of the 70 automatic type, that illustrated in association with the line 10 being indicated at A and that terminating the line 11 being illustrated in detail in Fig. 1 and being indicated generally at B.

Referring now more particularly to the equipment provided at the substation B, this substa-

tion comprises a ringing or signal device 17 connected across the line conductors 14 and 15 of the line 11 in series with a condenser 18; a transmitter 19, a receiver 20, an impulsing device 21 and a hook or cradle switch 22. The impulsing device 21 is of the conventional dial operated type and comprises a pair of impulsing springs 23, and three shunt springs 24, 25 and 26. The enumerated springs 24, 25 and 26 are normally restrained to the open circuit position as indicated in the drawings and are so arranged that the dial mechanism closes the same during operation of the impulsing device. Also included in the substation equipment is an auxiliary sound reproducing device in the form of a loud speaker 15 27. This device is provided with input terminals which are arranged to be connected across one winding 28 of a transformer 29 by means of a key operated switch 30 having two sets of contact springs and a common actuating member or key indicated by the dotted line 31. The key operated switch 30 is of the locking type in that when once operated to its off-normal position it remains in this position until it is manually restored to the normal position. The transformer 29 further comprises two windings 32 and 33 coupled to the winding 28 and arranged to be connected across the line terminals 15 and 16 of the substation B in series with a balancing network indicated generally at 34. As indicated, the transmitter 19 is connected across one winding 35 of an impedance matching transformer 36 in series with a condenser 37. The series-parallel circuit comprising the transformer winding 35, the condenser 37 and the transmitter 19, is, in turn, connected in series with a second winding 38 of the transformer 36 between the junction point of the two windings 32 and 33 and the substation input terminal 15.

Referring now to the operation of the system and assuming, for example, that a call is initiated at the substation A and routed by way of the automatic switching equipment provided in the exchange 12 and the line 11 to the substation B at a time when the last-mentioned substation is idle, when the line 11 is seized by one of the connector switches provided in the exchange 12 and tests idle, ringing current is projected over the line in the usual manner to actuate the ringing device 17, thereby to give an audible indication that the substation B is being called. The call may be answered in either of two ways, i. e., by removing the receiver 20 from its supporting hook or cradle, or by actuating the answer switch 30 to its off-normal position. If the call is answered in the usual manner by lifting the receiver 20 from its supporting hook or cradle, the springs 39 and 40 of the hook switch 22 are closed to connect the receiver 20 across the winding 28 of the transformer 29 and to connect a direct current bridge between the conductors 13 and 14 of the line 11. Specifically, this bridge extends from the terminal 15 by way of the transmitter 19, the transformer windings 38 and 33, the impulsing springs 23 and the cradle or hook switch springs 39 to the opposite substation line terminal 16. From an inspection of the drawings, it will be apparent that the receiver 20 is connected across the transformer winding 28 by way of the hook or cradle switch springs 40 and the springs 41 and 42 of the switch 30. The completion of the above traced bridging path across the conductors 13 and 14 of the line 11 causes the operated connector switch in the exchange 12 to respond to interrupt the ringing operation and complete a talk- 75

ing connection between the respective calling and called substations A and B.

As indicated above, the call as extended to the substation B may also be answered by operating the switch 30 to its off-normal position, without removing the receiver 20 from its supporting hook or cradle. In this case, the loud speaker 27 is connected across the winding 28 of the transformer 29 in lieu of the receiver 20. More particularly, the input terminals of the loud speaker 27 are connected across the winding 28 through closure of the springs 42 and 43 in response to the operation of the switch 30 to its off-normal position. In this case, the bridging path across the conductors 13 and 14 of the line 11 extend by way of the springs 44, which are closed in response to the operation of the switch 30, rather than by way of the springs 39 of the hook or cradle switch 22.

With either the receiver 20 or the loud speaker 27 operatively included in the substation circuit, talking battery is supplied to the substation circuit over the line 11 through the windings of the back bridge or called party relay embodied in the operated connector switch forming a part of the switch train by way of which the connection extends. The path of the signal currents incoming to the substation may be partially traced as extending by way of the line conductor 13, the balancing network 34, the two transformer windings 32 and 33, the impulsing springs 23 and the hook switch springs 39 or the key switch springs 44 to the opposite line conductor 14. Portions of the signal currents are, of course, by-passed through the branch circuit comprising the windings of the transformer 36. Alternating signal currents flowing through the windings 32 and 33 cause corresponding induced voltages to be developed in the winding 28 which are impressed on the receiver 20 or the input terminals of the loud speaker 27, depending upon which of the two translating devices is being used. Such voltages are reproduced by either of the two translating devices 26 and 27 in a well-known manner.

When sound waves impinge upon the diaphragm of the transmitter 19, undulating audio frequency currents corresponding to the sound waves are set up which cause corresponding voltages to be developed between the junction point of the two windings 32 and 33, and the line conductor 13. Such voltages cause currents to flow through the two windings 32 and 33 in opposite directions, the path of the current through the winding 32 extending from the junction point between the two windings 32 and 33 by way of this winding, the balancing network 34, the condenser 37 and the two transformer windings 35 and 38 back to the junction point between the windings 32 and 33. The path of audio currents flowing through the winding 33 extends from the line terminal 15 by way of the condenser 37, the two windings 35 and 38, the winding 33, the impulsing springs 23, the hook switch spring 39 or the key switch spring 44, the line conductor 14 and the loop circuit extending to the substation A back to the line terminal 15. By virtue of the improved arrangement of the balancing network 34, the audio frequency current traversing the winding 32 during operation of the transmitter 19 is substantially equal in magnitude and opposite in phase to the current traversing the winding 33 at all frequencies within the operating frequency range. The winding 28 is substantially equally coupled to the two windings 32 and 33 and,

hence, substantially no induced voltage is developed in the winding 28 during operation of the transmitter 19. Thus, the well-known anti-side-tone effect is obtained.

When the conversation ensuing over the connection between the two substations A and B is terminated and the connection is released, the apparatus provided at the substation B may be restored to normal by returning the receiver 20 to its supporting hook or cradle in the event it is being used as the sound translating device, or by restoring the switch 30 to normal in the event the loud speaker 27 is being used as the receiving means. If the receiver 20 is used and is restored to its supporting cradle or hook, the closed loop circuit extending to the operated switching equipment in the automatic exchange 12 is interrupted at the springs 39. Similarly, if the loud speaker 27 is used as the sound reproducing device, the loop circuit extending to the operated automatic switching equipment in the exchange 12 is interrupted at the springs 44 when the switch 30 is restored to normal. The manner in which the operated switch train in the automatic exchange is released of course depends upon the nature of the switching equipment. For example, this equipment may be designed so that the switch train utilized in an established connection is released when the answering party at the called substation hangs up. Alternatively this equipment may be designed so that the release of an operated switch train is under the control of the last party to hang up.

In order to initiate a call at the substation B intended for one of the other automatic substations such, for example, as the substation A, the calling party first closes a loop circuit extending to the switching equipment provided in the automatic exchange 12 by either removing the receiver 20 from its supporting cradle or hook to operate the switch 22 to its off-normal position, thereby to close the springs 39; or operating the switch 30 to its off-normal position to close the springs 44. The bridging path between the line conductors 13 and 14 established in response to either the operation of the switch 30 or the switch 22, is traced previously, and in either case the impulsing springs 23 are serially included in this path. When the bridging path between the line conductors 13 and 14 is completed, the associated or assigned non-numerical switch in the exchange 12 is caused to operate to extend the connection to one of the impulse-responsive numerical switches in the usual manner. During operation of the impulsing device 21 the impulsing springs 23 are alternately opened and closed, thereby to transmit impulses by way of the line 11 to the automatic switching equipment in the exchange 12. This equipment responds to the impulses in the usual manner to cause the connection to be routed by way thereof to the called line 10. During each operation of the impulsing device 21, or more particularly, during each digit dialed at the substation B, the shunt springs 24, 25 and 26 are moved to the closed circuit position. At the springs 25 and 26, the line conductor 13 is connected directly to the upper impulsing spring so that all circuit elements provided at the substation B are excluded from the impulsing circuit. At the springs 24 and 25 an obvious path is completed for short-circuiting the winding 28 by way of which energy is delivered to the loud speaker 27 and to the receiver 20, thus preventing microphonic noises from being reproduced by the one of these two translating devices which is 75

operatively included in the substation circuit. When the operation of the impulsing device 21 is ended, the springs 24, 25 and 26 are moved to the open circuit position in the usual manner, to interrupt the above-traced short-circuiting path across the winding 28 and to condition the substation circuit for voice frequency current transmission and reception. In this connection it will be apparent that if the selected called line 10 is tested by the automatic switching equipment in the exchange 12 and found busy, busy tone is returned over the calling loop circuit to traverse the windings 32 and 33 of the transformer 29, whereby a busy tone signal is generated by the 10 one of the two translating devices 20 and 27 which is operatively included in the substation circuit. If, on the other hand, the called line is idle and ringing current is projected thereover to signal the called substation in the usual manner, ring-back tone current is conducted back over the calling line and through the windings 32 and 33, so that a ring-back tone signal is produced by either the receiver 20 or the loud speaker 27. When the called subscriber answers, the desired 25 conversational connection is completed in the usual manner. The paths traversed by the signaling currents incoming and outgoing from the substation B on a call originated at this substation are exactly the same as those traced above for a call incoming to the substation B.

The improved arrangement of the balancing network 34, whereby the anti-side-tone circuit described above is substantially balanced at all 30 frequencies within the operating frequency range, may best be explained by reference to Fig. 2 wherein the circuit elements involved in an established communication connection between the substations A and B are shown. In the circuit of Fig. 2 the component network comprising the 35 two windings 35 and 38 of the transformer 36, the condenser 37 and the transmitter 19, is resolved into an equivalent series circuit comprising an inductance element 45 in series with a variable resistor 46. This equivalent circuit is 40 accurate for frequencies lying within the major portion of the voice frequency range. The series resistance of the line 11 is represented by the two resistors 47 and 48. shunt capacitance as represented by the condenser 64 are of relatively small effect as compared to the effect of the coupling capacitance 63 and the impedances of the circuit elements provided at the substation A in determining the frequency-impedance characteristic of the equivalent impedance of the network external to the substation B and connected between the terminals 15 and 16. Hence, to provide a simple resistance capacitance balancing network of the usual type in the circuit of the substation B would mean that the anti-side-tone circuit could only be effectively balanced for frequencies lying within a very small portion of the operating frequency range. To obviate this difficulty and to secure a more perfect balance of the anti-side-tone circuit when used in a system utilizing short lines, the improved coupling network 34 is provided.

In brief, the network 34 comprises a plurality of impedance elements 66, 67, 68, 69, 70, 71, 72 and Z_b which individually correspond to the impedance elements 62, 63, 64, 65, 55, 56, 57 and Z_a , in the order named, shown in the equivalent circuit of the Fig. 2a. More particularly, and considering Fig. 2, it will be observed that the criterion for maintaining the audio frequency currents flowing through the winding 32 equal in magnitude and opposite in phase to the corresponding audio frequency currents flowing through the winding 33 during operation of the transmitter or when audio frequency voltages are impressed across the resistor 46, is that the phase angle and magnitude of the equivalent impedance of the network 34 shall respectively be equal to the phase angle and magnitude of the equivalent impedance of the equivalent circuit shown in Fig. 2a, as measured between the terminals 15 and 16, at all frequencies within the operating frequency range. To this end, the resistance of the resistor 66 is made equal to the lumped series resistances of the two lines connecting the substations A and B as represented by the equivalent resistor 62; the resistance of the resistor 69 is made equal to the equivalent resistor 65; the capacitance of the condenser 68 is made equal to the equivalent capacitance 64; the capacitance of the condenser 67 is made equal to the combined capacitance 63 of the two coupling elements 58 and 51; the resistor 70 is made equal to the average value of the transmitter resistance as represented by the resistor 55; the induction coil 72 is a duplicate of the induction coil 57; the condenser 71 is chosen of a capacitance value equal to that of the condenser 56; and an artificial impedance element Z_b is provided, having a frequency-impedance characteristic which is a substantial duplicate of that of the impedance Z_a representing the receiver at the substation A.

If desired, the impedance Z_b may be of the form shown in Fig. 3. In brief, the element shown in Fig. 3 comprises two L-shaped core members 73 and 74 arranged in the manner illustrated so that two short air gaps 75 and 76 are provided between the oppositely disposed pole faces thereof. Wound respectively on the core members 73 and 74 are two coils 77 and 78 which are connected in series-aiding phase relation. The two terminals of the windings 77 and 78 are connected across the terminals of the winding of the transformer 72 shown as entering the box identified at Z_b . Specifically, the core members 73 and 74 with the windings 77 and 78 respectively wound thereon, may comprise standard receiver parts. The air

gaps 75 and 76 are preferably adjusted so that each has a length of approximately .025 inch.

By proportioning the impedance values of the elements included in the network 34 in the manner described, and by connecting these elements in a manner identical with the mode of connecting the elements of the equivalent circuit of Fig. 2a, the equivalent impedance of the balancing network 34 is caused to have substantially the same frequency-impedance characteristic as the frequency-impedance characteristic of the equivalent circuit shown in Fig. 2a, and hence, an entirely adequate balance of the anti-side-tone substation circuit is achieved for all frequencies within the operating frequency range. Obviously, an exact balance cannot be obtained for all possible communication connections for the reason that the impedance characteristics of different circuit elements embodied in different substations vary as do also the impedance characteristics of different lines. It is possible, however, by proportioning the impedance values of the elements embodied in the network 34 so that a substantially perfect balance is obtained when the substation B is connected through to a called line having average impedance characteristics, both with respect to the line itself and the circuit elements of the substation connected thereto, to obtain a sufficiently accurate balance of the anti-side-tone circuit, when connected to other lines, to prevent any substantial portion of the audio frequency energy developed by operation of the transmitter 18 from being reproduced by the receiver 20 or loud speaker 27 provided at this substation.

While it will be understood that the circuit specifications may vary according to the requirements of a particular system, the following specification of circuit constants for the network 34 are satisfactory when the network is included in a substation forming a part of a private automatic telephone system wherein the substation lines are short.

Resistance 66	50 ohms	45
Resistance 69	400 ohms	
Resistance 70	60 ohms	
Condenser 67	1 microfarad	
Condenser 68	.04 microfarad	
Condenser 71	1 microfarad	
Impedance Z_b	39 microhenries, 50 ohms D. C. resistance	50

While there has been described what is at present considered to be the preferred embodiment of the invention, it will be understood that various modifications may be made therein and it is intended to cover in the appended claims all such modifications as fall within the true spirit and scope of the invention.

What is claimed is:

1. In a telephone system including a first substation having a pair of line terminals adapted to be connected by way of a telephone line to another substation, and wherein the equivalent impedance, measured at said terminals, of impedances external to said first substation, is substantially determined by the impedances of the circuit elements included in said other substation; an anti-side-tone circuit included in said first substation and comprising a network for balancing the equivalent impedance across said terminals, said network comprising a plurality of impedance elements having impedances individually corresponding to certain of the component impedances making up said equivalent imped-

ance, and said plurality of impedances being so proportioned relative to their corresponding component impedances and being so connected and arranged that said anti-side-tone circuit is substantially balanced at all frequencies within the operating frequency range.

2. In a telephone system including a first substation having a pair of line terminals adapted to be connected by way of a telephone line to another substation, and wherein the equivalent impedance, measured at said terminals, of impedances external to said first substation, is substantially determined by the impedances of the circuit elements included in said other substation; an anti-side-tone circuit included in said first substation and comprising a network for balancing the equivalent impedance across said terminals, said network comprising a plurality of impedance elements having impedances individually corresponding to certain of the component impedances making up said equivalent impedance, and said plurality of impedances being so proportioned relative to their corresponding component impedances and being so connected and arranged that the frequency-impedance characteristic of said network is substantially similar to the frequency-impedance characteristic of said equivalent impedance.

3. In a telephone system including a first substation having a pair of line terminals adapted to be connected by way of a telephone line, the line connecting equipment of an exchange and a second line to another substation, and wherein the equivalent impedance, measured at said terminals, of impedances external to said first substation, is substantially determined by the impedances of the coupling elements embodied in said line connecting equipment and the impedances of the circuit elements included in said other substation; an anti-side-tone circuit included in said first substation and comprising a network for balancing the equivalent impedance across said terminals, said network comprising a plurality of impedance elements having impedances individually corresponding to certain of the component impedances making up said equivalent impedance, and said plurality of impedances being so proportioned relative to their corresponding component impedances and being so connected and arranged that said anti-side-tone circuit is substantially balanced at all frequencies within the operating frequency range.

4. In a telephone system including a first substation having a pair of line terminals adapted to be connected by way of a telephone line, the automatic switching equipment of an automatic exchange and a second line to another substation, and wherein the equivalent impedance, measured at said terminals, of impedances external to said first substation, is substantially determined by the impedances of the coupling elements embodied in said automatic switching equipment and the impedances of the circuit elements included in said other substation; an anti-side-tone circuit included in said first substation and comprising a network for balancing the equivalent impedance across said terminals, said network comprising a plurality of impedance elements having impedances individually corresponding to certain of the component impedances making up said equivalent impedance, and said plurality of impedances being so proportioned relative to their corresponding component impedances and being so connected and arranged that said anti-side-tone

circuit is substantially balanced at all frequencies within the operating frequency range

5. In a telephone system including a first substation having a pair of line terminals adapted to be connected by way of a telephone line to another substation, and wherein the equivalent impedance, measured at said terminals, of impedances external to said first substation, is substantially determined by the impedances of the circuit elements included in said other substation, at least two of which are of the reactance type; an anti-side-tone circuit included in said first substation and comprising a network for balancing the equivalent impedance across said terminals, said network comprising a plurality of impedance elements having impedances individually corresponding to certain of the component impedances making up said equivalent impedance, at least two of said impedance elements being of the reactance type and individually corresponding to different ones of said two circuit elements, and said plurality of impedances being so proportioned relative to their corresponding component impedances and being so connected and arranged that said anti-side-tone circuit is substantially balanced at all frequencies within the operating frequency range.

6. In a telephone system including a first substation having a pair of line terminals adapted to be connected by way of a telephone line, the line connecting equipment of an exchange and a second line to another substation, and wherein the equivalent impedance, measured at said terminals, of impedances external to said first substation, is substantially determined by the impedances of the coupling elements embodied in said line connecting equipment and the impedances of the circuit elements included in said other substation, at least two of which are of the reactance type; an anti-side-tone circuit included in said first substation and comprising a network for balancing the equivalent impedance across said terminals, said network comprising a plurality of impedance elements having impedances individually corresponding to certain of the component impedances making up said equivalent impedance, at least two of said impedance elements being of the reactance type and individually corresponding to different ones of said two circuit elements, and said plurality of impedances being so proportioned relative to their corresponding component impedances and being so connected and arranged that said anti-side-tone circuit is substantially balanced at all frequencies within the operating frequency range.

7. In a telephone system including a first substation having a pair of line terminals adapted to be connected by way of a telephone line, the line connecting equipment of an exchange and a second line to another substation, and wherein the equivalent impedance, measured at said terminals, of impedances external to said first substation, is substantially determined by the reactance of the coupling elements embodied in said line connecting equipment, the resistive impedance of the transmitter at said other substation and the reactive impedance of the induction coil and receiver at said other substation; an anti-side-tone circuit included in said first substation and comprising a network for balancing the equivalent impedance across said terminals, reactive impedance elements included in said network and corresponding to said coupling elements, said induction coil and said receiver, and a resistive impedance element in

cluded in said network and corresponding to said transmitter, said elements of said network being so proportioned relative to the corresponding elements of said other substation and being so connected and arranged that said anti-side-tone circuit is substantially balanced at all frequencies within the operating frequency range.

8. In a telephone system including a first substation having a pair of line terminals adapted to be connected by way of a telephone line, the line connecting equipment of an exchange and a second line to another substation, and wherein the equivalent impedance, measured at said terminals, of impedances external to said first substation, is substantially determined by the reactance of the coupling elements embodied in said line connecting equipment, the resistive impedance of the transmitter at said other substation and the reactive impedance of the induction coil and receiver at said other substation; an anti-side-tone circuit included in said first substation and comprising a network for balancing the equivalent impedance across said terminals, reactive impedance elements included in said network and corresponding to said coupling elements, said induction coil and said receiver, a resistive impedance element in said network and corresponding to said transmitter, and additional impedance elements in said network individually corresponding to the lumped series resistances of said first and second lines and to the lumped shunt capacitance of said first and second lines, said elements of said network being so proportioned and being so connected and arranged that said anti-side-tone circuit is substantially balanced at all frequencies within the operating frequency range.

9. In a telephone system including a first substation having a pair of line terminals adapted to be connected by way of a telephone line, the line connecting equipment of an exchange and a second line to another substation, and wherein the equivalent impedance, measured at said terminals, of impedances external to said first substation, is substantially determined by the impedances of the coupling elements embodied in said line connecting equipment and the impedances of the circuit elements included in said other substation; an anti-side-tone circuit included in said first substation and comprising a network for balancing the equivalent impedance across said terminals, said network comprising impedance elements individually corresponding to said coupling elements and to the circuit elements at said other substation, and additional impedance elements in said network individually corresponding to the lumped series resistance of said first and second lines and to the lumped shunt capacitance of said first and second lines, said elements being so proportioned and being so connected and arranged that said anti-side-tone circuit is substantially balanced at all frequencies within the operating frequency range.

10. In a telephone system including a first substation having a pair of line terminals adapted to be connected by way of a telephone line, the line connecting equipment of an exchange and a second line to another substation, and wherein the equivalent impedance, measured at said terminals, of impedances external to said first substation, is substantially determined by the impedances of the coupling elements embodied in said line connecting equipment and the impedances of the circuit elements included

in said other substation; an anti-side-tone circuit included in said first substation and comprising a network for balancing the equivalent impedance across said terminals, a transformer included in said anti-side-tone circuit and including a plurality of windings, a sound reproducing device coupled to one of said windings, and a transmitter included in said anti-side-tone circuit, said network comprising impedance elements individually corresponding to said coupling elements and to the circuit elements at said other substation, said elements being so proportioned and being so connected and arranged that said anti-side-tone circuit is substantially balanced at all frequencies within the operating frequency range, whereby substantially no audio frequency energy is delivered to said reproducing device during operation of said transmitter.

11. In a telephone system including a first substation having a pair of line terminals adapted to be connected by way of a telephone line, the line connecting equipment of an exchange and a second line to another substation, and wherein the equivalent impedance, measured at said terminals, of impedances external to said first substation, is substantially determined by the impedances of the coupling elements embodied in said line connecting equipment and the impedances of the circuit elements included in said other substation; an anti-side-tone circuit included in said first substation and comprising a network for balancing the equivalent impedance across said terminals, a transformer included in said anti-side-tone circuit and comprising a plurality of windings, a sound reproducing device coupled to one of said windings, a transmitter included in said anti-side-tone circuit, said network comprising impedance elements individually corresponding to said coupling elements and to the circuit elements at said other substation, and additional impedance elements in said network individually corresponding to the lumped series resistance and the lumped shunt capacitance of said first and second lines, said elements being so proportioned and being so connected and arranged that said anti-side-tone circuit is substantially balanced at all frequencies within the operating frequency range, whereby substantially no audio frequency energy is delivered to said reproducing device during operation of said transmitter.

12. A balancing network adapted for use in a telephone substation circuit of the anti-side-tone type which comprises, in combination, an artificial receiver having a substantially non-linear frequency-impedance characteristic simulating in form the frequency-impedance characteristic of an actual receiver, an induction coil, a resistor having a resistance substantially approximating the average effective resistance of a transmitter, and additional impedance elements corresponding to the reactive and resistive impedances of two connected telephone lines interconnecting said substation with a distant substation, said artificial receiver, induction coil, resistor and additional impedance elements being so related and the impedances thereof being so proportioned that the equivalent impedance thereof substantially matches the equivalent impedance of said lines and the elements provided at said distant substation at all frequencies within the operating frequency range.

HAROLD CHARLES PYE.
